UNITED STATES PATENT OFFICE.

JOSÉ GUARDIOLA, OF CHOCOLA, GUATEMALA.

COFFEE-HULLER.

SPECIFICATION forming part of Letters Patent No. 340,039, dated April 13, 1886.

Application filed June 8, 1885. Renewed March 17, 1886. Serial No. 195,613. (No model.)

To all whom it may concern:

Be it known that I, JOSÉ GUARDIOLA, of Chocola, Guatemala, have invented a new and Improved Coffee-Huller, of which the following is a full, clear, and exact description.

The object of my invention is to provide a new and improved machine for hulling coffee.

The invention consists of the combinations of parts substantially as hereinafter described, and pointed out in the claims.

Reference is to be had to the accompanying drawings, forming part of this specification, in which similar letters of reference indicate corresponding parts in all the figures.

Figure 1 is a longitudinal sectional elevation of my improved coffee-huller. Fig. 2 is a face view of the smaller end. Fig. 3 is a face view of the larger end of the inner section.

The shaft A is rigidly held in suitable supports in such a manner that it cannot revolve, and on the said shaft is loosely mounted a sleeve, B, on which a disk, C, is formed, and from the outer surface of which a ring or annular flange, D, projects, forming a belt-pulley. A conical or tapered circular sheet-metal shell, E, has its smaller end secured by angle-irons or otherwise to the inner surface of the disk C, and a ring, F, preferably made of cast-iron, is secured on the shell E at the wider end. The shell E is provided on its inner surface with projections *a*, which may be produced in different ways.

On the shaft A two disks or wheels, G, are rigidly mounted, and are united by wooden staves H, secured on the rims and forming a cone-frustum, J, parallel with but smaller than the shell E. On about one-third of the periphery of inner conical part, J, steel plates or graters K are held by leather or other flexible strips, K', or other hinges, in rows extending from end to end of the part E, so that two-thirds of the outer surface of the conical part J are smooth or uncovered.

The plates K are pressed from the outer surface of the part J by semi-elliptical or other springs, L, interposed between the surface of the part J and the plates K, and upon the outer surface of the said plates projections *b* are formed. The free edges of the plates K are slightly curved toward the staves H.

A circular plate, M, connected with the larger wheel G, closes the end of the shell E,

the ring F of the shell E revolving around the rim of the plate M.

An inclined chute, N, passes through the wheels G from the upper part of the larger end of the machine down to the lower part of the smaller end, and is held entirely by the part J. A hopper, O, is formed on the upper end of the chute N, and a gate, P, is provided, by means of which the chute N can be closed a short distance below the hopper. A small chute, Q, is formed on the bottom of the plate M, and is provided with a gate, R.

When the machine is mounted, the chord 65 uniting the ends of the segment formed by the staves H, on which the plates K are held, must be vertical, or nearly so.

The coffee, &c., to be hulled slides from the hopper O through the chute N into the space 7c at that end of the shell E and into the annular space between the shell E and the part J, and, the shell E being revolved, the coffee is hulled.

The material is discharged at the larger end 75 of the cone, and moves toward the same by the slant of the shell E and by the rotation of the said shell.

In operation, the coffee is taken round by the centrifugal force of the rotating shell E, 80 and, being moved along past the plates K, they contribute to hull and polish the coffee in its passage between them and the shell E, helped by the projections above mentioned. To prevent the breaking of any of the coffee, the 85 springs placed under the plates K yield in proportion to the amount of coffee that is passed.

Having thus described my invention, what I claim as new, and desire to secure by Letters 90 Patent, is—

1. In a coffee-huller, the combination, with a revolving shell having projections on its inner surface, of a fixed conical part within the shell having grating-plates on its outer surface, substantially as herein shown and described. 95

2. In a coffee-huller, the combination, with a revolving conical shell having projections on its inner surface, of a fixed conical part 100 within the shell, grating-plates on the inner conical part, and a feed-chute extending through the inner conical part, substantially as herein shown and described.

3. In a coffee-huller, the combination, with the fixed shaft A, of the sleeve B, the disk C, the pulley D, the conical shell E, provided with projections on its inner surface, and the 5 fixed conical part J within the shell, substantially as herein shown and described.

4. In a coffee-huller, the combination, with the fixed shaft A, of the sleeve B, the disk C, the shell E, the ring F on the free end of the 10 same, and the conical part J within the shell, substantially as herein shown and described.

5. In a coffee-huller, the combination, with the fixed shaft A, of the sleeve B, the disk C, the shell E, the ring F, the wheels G, the 15 staves H, and the plate M, substantially as herein shown and described.

6. In a coffee-huller, the combination, with the fixed shaft A, of the sleeve B, the disk C,

the shell E, the ring F, the plate M, having a chute Q, the wheels G, the staves H, the chute 20 N, and the hopper O, substantially as herein shown and described.

7. In a coffee-huller, the combination, with a revolving shell having projections on its inner surface, of a conical part within the shell, 25 plates hinged on the conical part and provided with projections on their outer surfaces, and springs to give to the plates the proper elasticity in the direction from the surface on which they are hinged, substantially as here- 30 in shown and described.

J. GUARDIOLA.
